UNITED STATES PATENT OFFICE.

EDMUND L. ZALINSKI, OF THE UNITED STATES ARMY.

ARTILLERY-CARTRIDGE.

SPECIFICATION forming part of Letters Patent No. 487,400, dated December 6, 1892.

Application filed June 19, 1888. Serial No. 277,517. (No model.)

To all whom it may concern:

Be it known that I, EDMUND L. ZALINSKI, of the United States Army, stationed at Fort Hamilton, State of New York, have invented 5 certain new and useful Improvements in Artillery-Cartridges, of which the following is a specification, reference being had therein to the accompanying drawings.

This invention relates to cartridges for 10 heavy ordnance; and it consists in the construction, substantially as hereinafter described, by which a slow combustion of powder is maintained, and the pressure is kept up for a considerable time or until the projectile has reached the muzzle of the gun.

The cartridge may be used as an auxiliary to a pneumatic cannon or as an accelerating charge in any gun. The object is to maintain a relatively-low but uniform or increasing 15 pressure in the bore of the gun.

Figure 1 is a longitudinal section of a gun with cartridge-chamber considerably enlarged. Fig. 2 is a front view of a cartridge, illustrating my invention. Fig. 3 is a longitudinal section of a similar cartridge. Fig. 4 20 illustrates a device for using the cartridge in connection with the air-pressure in a pneumatic cannon. Fig. 5 illustrates a mechanism for using the cartridge as an accelerating charge. Fig. 6 is a rear view, partly broken 25 away, of a modification.

A indicates the barrel or tube of a gun; B, the gas-supply pipe leading to the tube of a gas-pressure gun.

30 A cartridge C is made of a material which has little tendency to transmit heat. Compressed paper is such a material. The cartridge C is a cylinder of size to fit the powder-chamber in a gun. The cylinder has a central 35 passage D, provided with a large number of radial chambers E, and preferably a number of chambers F, parallel with the axis of the cylinder and pointing forward. All the chambers D E are filled with gunpowder, preferably a slow-burning quality. As the chambers are separated from each other by the 40 partitions H the powder-charges therein contained will burn independently of each other. The powder-charges for each chamber D E 45 may be a small cartridge—say a little more than a musket-charge for guns of small caliber—contained in a paper or similar casing.

The charges in chambers F are ignited by wires G, which wires communicate with an electric battery outside the gun. The ignition of a few chambers F serves to ignite all the charges in chambers E, and all the charges burn, the radial charges burning from the central passage D toward the periphery of the cartridge. The longitudinal chambers F may 55 be dispensed with; but for convenience I prefer that they shall be present in the cartridge even if they are left unfilled with powder.

The preferable construction of shell or casing is shown in Fig. 6. The chambers E' in 60 this instance are conical or fan-shaped, increasing in diameter or width toward the periphery. The central portion C' of the casing has these chambers formed therein and may be loaded with the powder-charges and 65 then slipped into the ring or hollow cylinder C², thus completing the cartridge. Then when the charges are ignited along the passage D the gases of combustion will pass through the small apertures at the inner ends 70 of chambers E' and into passage D and so along the bore of the gun. As the size of chambers E' increases toward the periphery, the burning-surface of the powder-charge is 75 constantly increasing, and consequently the gas is developed with greater rapidity as the 80 velocity of the projectile increases, thus maintaining an approximately-uniform pressure. By igniting the front chambers first and permitting the rearward chambers to be ignited 85 therefrom, the combustion of the charge may be extended over a longer interval of time.

I am aware that it has been proposed to use in artillery firing a compressed powder-charge consisting of a hollow cylinder of powder to be ignited at the center, and as the combustion extended outward in increasing circles the pressure of gas increased. Such charges have hitherto proved unreliable, for the probable reason that the great pressure 90 developed at the start breaks up the cylinder and practically crushes it into fine powder, 95 which burns explosively and not slowly, as intended.

The object of my cartridge-casing is to subdivide and practically insulate each of the powder-charges from the others, both as to heat and explosive effect. The casing should therefore be strong enough, when sustained 100

by the walls of the gun, to prevent the bursting of one chamber into another and be sufficiently a non-conductor of heat to prevent the ignition of one charge from another by 5 conducted heat. Pressed paper for the part C' will do well. Metal will do if the chambers are lined with paper or asbestos.

In Fig. 4 the device is shown in connection with a pneumatic cannon. The projectile P is given its first impulse by air or similar pressure through supply-pipe B. When the projectile reaches the pin Q, which extends through a hole into the bore, the pin is pressed out, a battery-circuit is closed, as at R, and 10 through wires the cartridge is fired by usual appliances well known in the art. By this means a torpedo or projectile containing a sensitive high explodent may be started with 15 a low pressure and the pressure greatly increased when the projectile is well under way.

In Fig. 5 an auxiliary chamber A' may contain the cartridge C and the gases of combustion pass through the diminished passage A² to the bore of the gun in which the projectile is placed, either with or without a starting-charge.

What I claim is—

1. In combination with the bore of a gun and communicating therewith, a cartridge 30 having a casing composed of a material which is a non-conductor of heat and a plurality of permanent charge-containing chambers in said casing, said chambers communicating to a single passage which communicates to the 35 bore of the gun in rear of the projectile, all substantially as described.

2. A permanent cartridge-casing for explosive charges, having a plurality of charge-chambers and composed of material strong 40 enough to withstand the firing of the con-

tained powder-charges, and a sufficient non-conductor of heat, so that one charge may not ignite another by heat radiated through the casing, substantially as described.

3. A cartridge for heavy guns, consisting of 45 a cylindrical body having a longitudinal passage and a plurality of chambers radiating therefrom and closed at their outer ends, said body being of a material which cannot be ruptured by the explosion of the charges, sub- 50 stantially as described.

4. A cartridge for heavy guns, consisting of a permanent casing having a passage which opens in a direction toward the bore of the gun and in rear of the projectile when the 55 cartridge is used in a gun, said casing having a plurality of permanent chambers opening into this main chamber and each supplied with an explosive charge, substantially as described.

5. The cylindrical cartridge-casing having a central passage and a plurality of practically-radial passages communicating therewith, and an inclosing ring covering the outer 60 ends of the radial chambers, substantially as 65 described.

6. The cartridge-casing having a central passage and a plurality of practically-radial chambers communicating therewith, said chambers being of greater diameter toward 70 their outer ends, and a ring or casing closing the outer ends of these chambers, all substantially as described.

In testimony whereof I affix my signature in presence of two witnesses.

EDMUND L. ZALINSKI.
